(57) **CLAIM**

I claim the ornamental design for “fishing rod”, as shown and described.

DESCRIPTION

FIG. 1 is a perspective view of a fishing rod;

FIG. 2 is a bottom view of the fishing rod;

FIG. 3 is a top view of the fishing rod;

FIG. 4 is a first side view of the fishing rod;

FIG. 5 is a second side view of the fishing rod;

FIG. 6 is a third side view of the fishing rod;

FIG. 7 is a fourth side view of the fishing rod; and,

FIG. 8 is an environmental view of the fishing rod.

The broken lines illustrate portions of the design that are included for the purpose of illustrating only and form no part of the claimed design.

The fishing rod is shown with a center break to indicate indeterminate length.

“Characteristic features” of the design are the result of a fishing rod defined by a transition between an approximately triangular prism at the fishing rod’s butt-end and an approximately cylindrical tip.
